UNITED STATES PATENT OFFICE.

FREDERICK I. MONKS, OF HOUSTON, TEXAS.

MATTRESS-SUPPORT.

1,353,260.

Specification of Letters Patent. Patented Sept. 21, 1920.

Application filed November 3, 1919. Serial No. 335,394.

To all whom it may concern:

Be it known that I, FREDERICK I. MONKS, citizen of the United States, residing at Houston, in the county of Harris and State 5 of Texas, have invented certain new and useful Improvements in Mattress-Supports, of which the following is a specification.

This invention relates to new and useful improvements in a mattress support.

10 One object of the invention is to provide a resilient mattress support, designed to take the place of the ordinary spring now in common use and it is formed of inflatable units arranged to be inflated by the use of air, hot 15 or cold water or other similar fluids.

With the above and other objects in view, the invention has particular relation to certain novel features of construction, arrangement of parts and use, an example of which 20 is given in this specification and illustrated in the accompanying drawings wherein:

Figure 1, is a plan view of the device and.

Fig. 2, is a transverse sectional view, taken on the line 2—2 of Fig. 1.

25 Referring now more particularly to drawings wherein like numerals of reference designate similar parts in each of the figures, numeral 1 refers to the bottom of the frame work, said frame work having the side members 2, 2, and the end members 3, 3. The frame work, also has a plurality of lengthwise ribs 4, 4 spaced apart and forming partitions. Between these partitions are the 30 series of inflatable units 5, which are preferably spherical in form and are composed of elastic material, such as rubber. The units of each series are connected by tubes, such as 6.

Each row of units is independent of the 40 others, so that the support may be made of any desired width corresponding to the

width of the mattress 7, which is supported thereon. Each row of units is provided at one end with an inlet valve 7, so that the inflating fluid may be introduced into the 45 units to inflate them and when so inflated they are of a size to hold the mattress a safe distance above the partitions 4 as illustrated in Fig. 2. Either air or water may be used to inflate the units 5 and in some cases hot 50 water will be used, when the device is used for hospital purposes. When water is used to inflate the units, an outlet valve as 8 is connected to each row of units at the end opposite the inlet valve 7, so that the water 55 may be readily drained therefrom, and when hot water is used as an inflating fluid a much thinner mattress will be used than that indicated in Fig. 2, so that the patient will obtain beneficial results from the heat. 60

What I claim is:

A mattress support including a framework formed with a bottom, side and end members, lengthwise ribs extending transversely between the side members and spaced 65 apart, forming parallel compartments, said side and end members extending up above the partitions and forming a mattress retainer, a series of inflatable units arranged in each compartment, said units being 70 formed of elastic material, fluid conducting tubes connecting the units of each series, a fluid inlet and a fluid outlet connected to each series of units and valves controlling said inlet and said outlet. 75

In testimony whereof I have signed my name to this specification in the presence of two subscribing witnesses.

FREDERICK I. MONKS.
